GODFRIED J. MAYER, OF BUFFALO, NEW YORK.

MECHANISM FOR OPERATING SCREW MACHINES AND THE LIKE.

Application filed June 26, 1925. Serial No. 89,735.

My invention relates to screw machines, and more particularly to mechanism for operating the same.

Screw machines invariably are provided with chuck-operating or combined chuck-operating and stock-feeding levers and with slide or cut-off levers, the first movable horizontally through an arc of a circle and the second vertically through an arc of a circle. Both levers are invariably operated with the left hand, due to the fact that the right is required to operate the turret. Considerable time is consumed and waste effort employed in so manipulating a screw machine, and consequently the machine cannot be operated to its full capacity.

The object of my invention is to provide a machine in which provision is made for operating both levers without moving the hand of the operator from one lever to the other and so that the right hand will always be free to operate the turret, or for use in any other manner.

Another object of my invention is to provide an operating connection between the two levers, and to operate one from the other.

A still further object of my invention is to provide a connection between the two levers so that one may operate independent of the other, and when operated in a certain manner will cause operation of said other lever.

A still further object of my invention is to provide means for operating the chuck and feeding stock and for operating the slide or cut-off from a single point.

A still further object of my invention is to provide a connection between the slide or cut-off lever and the stock-feeding and chuck-operating mechanism whereby the operator, upon grasping the slide or cut-off lever, will be able to feed stock, operate the chuck, and operate the tool post slide or cut-off, with said slide or cut-off lever.

A still further object of my invention is to provide in a screw machine, a slide or cut-off lever and arrange the same for movement in planes at an angle to each other, and to provide connection between said slide or cut-off lever and the stock-feeding and chuck-operating mechanism so that the latter will be operated upon movement of said slide or cut-off lever in one direction, and so that the slide or cut-off only will be operated upon movement of said last-mentioned lever in a second direction.

With the above, and other objects in view

to appear hereinafter, the invention consists in the novel features of construction and in the arrangement and combination of parts to be hereinafter described and more particularly pointed out in the subjoined claims.

In the drawings:

Fig. 1 is a perspective view of a portion of a screw machine.

Fig. 2 is a sectional plan view of the same with parts omitted.

Fig. 3 is a transverse section taken on line 3—3, Fig. 2.

Fig. 4 is an enlarged section taken on line 4—4, Fig. 2.

Fig. 5 is an enlarged longitudinal section taken on line 5—5, Fig. 2.

The screw machine shown is one of many different makes of machines of this type now in use, wherein a horizontally or substantially horizontally-swinging lever is employed for feeding stock and for operating the chuck to hold the stock fed therethrough, and wherein also a vertically-swinging lever is employed to operate the cut-off, which includes the tool post slide of the machine.

In the drawings, 6 designates the bed of the machine having legs 7 integral therewith for supporting the bed and parts mounted thereon, and 8 is a pan-like table with which machines of this type are usually equipped.

The bed of the machine has integral therewith a head stock 9, which includes the front and rear spindle bearings 10 and, as is common in machines of this type, the spindle through which stock 11 is fed is journaled in said bearings and the chuck 12 secured to said spindle. The spindle has mounted thereon the usual cone pulley 13. Suitable stock-feeding and chuck-operating mechanism 14 is provided, which, when actuated, operates the chuck and feeds the stock through the chuck so as to project therethrough and come in contact, if desired, with centering mechanism on a turret (not shown).

As a turret is a part common to all screw machines, it has not been deemed necessary to illustrate the same and as my invention does not relate to any particular type of stock-feeding and chuck-operating mechanism, only sufficient of a common type thereof is shown to illustrate the use of my invention.

Cut-off mechanism is provided with the usual slide member 15 longitudinally movable along ways on the bed, and mounted on said slide member is a transversely movable tool-post slide 16 having the tool post 17

thereon, and a suitable tool 18 fastened therein for operating upon the stock fed through and extending from the chuck.

The tool-post slide is provided with a gear rack, and as well known, a rock-shaft is journaled in bearings on the slide member 15 on which is suitably secured a gear segment 19 meshing with the gear rack on the tool-post slide. In some machines other mechanical elements are employed to serve the purpose of the rack and segment arrangement referred to, but my invention is adaptable to machines of various makes.

20 designates the slide or cut-off lever also secured to said rock-shaft, and as one adaptation of my invention. This lever may be said to be articulated, since it comprises an inner part 21 and an outer part 22 pivotally connected to said inner part, the pivot being such that upon moving the outer part in a vertical plane the inner part will move with the same and operate the gear segment, which in turn will move the tool-post slide to the desired position and feed the same to, into, or through the stock, as the case may be. The pivotal connection of the two parts of this lever is such that the outer part may swing through an arc of a circle in a substantially horizontal direction without moving the inner part of said lever. The movement of the lever in a vertical direction is indicated by full and dotted lines in Fig. 3, while the movement of the lever in a horizontal direction, or in a longitudinal direction when considered with reference to the complete machine, is indicated by dotted lines in Fig. 2.

23 designates the stock-feeding and chuck-operating lever, and in this instance said lever is shown as pivotally secured to the head stock of the machine at 24. Pivotally connected to this lever at a point a slight distance from its pivot, is a link 25, one end of which is pivotally connected to said lever and the other end to a longitudinally-movable element 26 forming part of the stock-feeding and chuck-operating mechanism.

A connection is provided between the slide or cut-off lever 20 and the stock-feeding and chuck-operating lever 23, and this connection is preferably in the form of a rod 27 constructed in two sections 28, 29, adjacent ends of the section being oppositely threaded and having a turn buckle 30 threaded thereon so that the rod may be lengthened or shortened, as may be required.

This rod is flexibly connected with the two levers 20 and 23, and preferably each of these levers has a clamp 31 fastened thereto, which may be positioned at any desired point along the length of the lever to which it is applied. Each of these clamps is provided with a stud 32 terminating in a ball 33, and the ends of the connector rod are provided with sockets 34 into which the balls of said studs are entered, a screw plug 35 being threaded into

each end of the rod to retain the rod on said studs while permitting movement of the slide or cut-off lever 20 in one direction without imparting such movement to the stock-feeding or chuck-operating lever 23, and so that upon movement of said slide or cut-off lever, or a part thereof in another direction, the stock-feeding and chuck-operating lever will be caused to operate and impart its movement to the stock-feeding and chuck-operating mechanism for feeding the stock through the chuck and for operating the chuck to hold the stock in proper position.

It will be understood that in operating a machine equipped with my invention, it is simply necessary to grasp the slide or cut-off lever 20 with the left hand, move said lever from the position shown in full lines in Fig. 2 to that shown in dotted lines. This will cause the stock-feeding and chuck-operating lever 23 to be moved from the position shown in full lines in Fig. 2 to that shown in dotted lines, whereupon the chuck will have been opened and the stock fed through the chuck to the desired extent; and upon moving said lever 23 from the dotted position shown in Fig. 2 to that shown in full lines in said figure, the chuck will become closed and grip the stock so that it will be rotated with the spindle and be ready to be operated upon by the tool fastened in the tool-post for the purpose. The slide or cut-off lever 20 may then be swung from the position shown in full lines in Fig. 3 to that shown in dotted lines, or approximately so, which will cause the tool-post slide 16 to be moved on the slide member 15 of the cut-off mechanism to bring the tool in position against the stock, and by gradually feeding the tool forward, the desired operation will take place.

It is of course understood that the tool-post slide may have two tool posts, one operating to produce a desired effect on the stock without severing any portion thereof, and the other may be used for cutting off the stock so that movement of the slide or cut-off lever 20 in one direction will bring one tool against the stock, and movement thereof in the other direction will bring a cut-off tool in contact with the stock to sever the portion of the stock operated upon from the portion extending through the spindle of the machine.

In the drawings, only one tool post is shown, but it is of course understood that at times two tool posts will be used, all of which will be understood by those familiar with the art.

When a single tool post is used on the tool post slide, the tool therein may be used for shaping or otherwise machining stock to desired form and also to cut off stock; therefore in the claims the term "cut-off lever" is not to be construed in a restrictive sense, since it operates the tool post slide and consequently may serve for various purposes.

It will be apparent from the foregoing that the two operating levers of a screw machine are operatively connected together, and that one of the said levers, or at least a portion 5 thereof, may be moved in one direction to cause operation of the other lever, or it may be moved in another direction independent of said other lever and without causing movement of the latter; also that the connection 10 between said levers may be lengthened or shortened and that the points of attachment of said connection to either or both levers may be changed so that the movements of said 15 levers may be varied to produce the desired results.

The construction and arrangement of parts shown and described is merely representative of my invention, and manifestly, these may be varied without departing from the spirit 20 of my invention or sacrificing any of the advantages thereof.

Having thus described my invention, what I claim is:—

1. In a screw-machine or the like having 25 two operating parts, two operating levers separately operable for manipulating said operating parts, and a rigid connection between said operating levers having universal and adjustable connection with and along 30 said levers.

2. In a screw-machine or the like, a cut-off lever movable bodily in one direction and having part thereof movable separately in another direction, a second operating lever 35 functioning for a purpose different from said cut-off lever, and connection between said second operating lever and the separately movable part of said cut-off lever.

3. In a screw-machine or the like, a cut-off lever bodily movable and having a part thereof of separately movable, a second lever functioning for a purpose different from said cut-off lever, and means of connection between the separately movable part of said cut-off 45 lever and said second lever for operating the latter from said separately movable part.

4. In a screw-machine or the like, a cut-off lever having an effective movement for operating cut-off mechanism and an ineffective movement independently of said cut-off 50 mechanism, an operating lever spaced from said cut-off lever and functioning for a purpose different from said cut-off lever, and connection between said two levers operable from said cut-off lever only during the ineffective movement of the latter. 55

5. A screw-machine or the like having a cut-off lever vertically movable bodily through an arc of a circle to operate cut-off mechanism and having a part thereof movable separately through an arc of a circle at an angle to the bodily movement of said lever, a chuck operating lever movable through an arc of a circle at an angle to the bodily movement of said cut-off lever, and a rod having 60 universal connection at opposite ends with the separately movable part of said cut-off lever and said chuck-operating lever. 65

6. A screw-machine or the like having a cut-off lever bodily movable to operate cut- 70 off mechanism and provided with a separately movable part, a second operating lever functioning for a purpose different from said cut-off lever, a connecting rod connecting said levers, and means for changing the point 75 of connection of said rod to one of said levers.

7. A screw-machine or the like having a cut-off lever bodily movable to operate cut-off mechanism, a second operating lever functioning for a purpose different from said cut-off 80 lever, and a connecting rod connecting said levers and being universally and adjustably connected with said levers.

8. In a screw machine or the like having two operating parts, two operating levers for 85 manipulating said operating parts, and a rigid connection between said operating levers having a universal and adjustable connection at one end with and along one of said operating levers. 90

In testimony whereof I affix my signature.

GODFRIED J. MAYER.
